UNITED STATES PATENT OFFICE

147,459

DESIGN FOR A SCOOP FOR POPCORN, CANDIES, PEANUTS, AND THE LIKE

Arthur Kloth, San Francisco, Calif.

Application April 29, 1946, Serial No. 129,080

Term of patent 14 years

(Cl. D44—29)

To all whom it may concern:

Be it known that I, Arthur Kloth, a citizen of the United States of America, residing at San Francisco, in the county of San Francisco and State of California, have invented a new, original, and ornamental Design for a Scoop for Popcorn, Candies, Peanuts, and the like, of which the following is a specification, reference being had to the accompanying drawing, forming a part thereof.

The figure is a perspective view of a scoop for popcorn, candies, peanuts, and the like, showing my new design.

I claim:

The ornamental design for a scoop for popcorn,

candies, peanuts, and the like, substantially as shown.

ARTHUR KLOTH.
